UNITED STATES PATENT OFFICE

2,367,601

HAIR DRIER AND DEHYDRATOR

Walter D. Nicol, Austin, Minn.

Application February 4, 1942, Serial No. 429,567

5 Claims. (Cl. 34—79)

This invention relates to a hair drying apparatus.

An object of this invention is to provide a hair drier wherein the moisture is withdrawn from the hair and collected in a receiver.

Another object of this invention is to provide a suction device for removing moisture from the hair without discomfort.

A further object of this invention is to provide a device of this kind including means for discharging heated air onto the hair at the same time that the moisture is being removed.

A further object of this invention is to provide an improved suction hood or nozzle for use with a dehydrating device of this kind.

To the foregoing objects and to others which may hereinafter appear, the invention consists of the novel construction, combination and arrangement of parts as will be hereinafter referred to and illustrated in the accompanying drawings, wherein is shown an embodiment of the invention, but it is to be understood that changes, variations and modifications may be resorted to which fall within the scope of the invention as claimed.

In the drawings:

Figure 1 is a detail side elevation partly broken away of a hair drier and dehydrator constructed according to an embodiment of this invention,

Figure 2 is a fragmentary top plan of the device.

Figure 3 is an enlarged vertical section of the suction member with the moisture collector connected thereto,

Figure 4 is a bottom plan of the suction and drying nozzle or hood,

Figure 5 is a sectional view taken on the line 5—5 of Figure 4,

Figure 6 is a sectional view taken on the line 6—6 of Figure 2, and

Figure 7 is a fragmentary sectional view taken on the line 7—7 of Figure 2.

Referring to the drawings, the numeral 10 designates generally a base structure which includes a base plate 11 formed with downwardly extending end flanges 12 and downwardly extending side flanges 13. A suction member generally designated as 14 is mounted on the base member 10 and comprises a hollow base 15 formed with lower base flanges 16 which are secured by fastening devices 17 to the base plate 11.

A cylinder 18 is mounted on top of the base 15 and is provided with a plurality of heat dissipating vanes or blades 19. A piston 20 is slidably in the cylinder 18 and is connected to a crank shaft 21 by means of a connecting rod 22. The cylinder 55

18 has detachably secured to the upper end thereof a head 23 which is secured to the cylinder 18 by fastening devices 24. The head 23 has an intake port 25 formed therein which is normally closed by a spring-pressed valve 26. An upstanding cylindrical boss 27 is formed integral with the head 23 and extends upwardly from the intake port 25. The boss 27 is formed with a flange 28 on which a cylindrical connector 29 is adapted to be secured. The connector 29 is formed with a lower flange 30 secured by fastening devices 31 to the flange 28. A valve stem guide member 31 is mounted within the upper end portion of the boss 27 through which the valve stem 32 slidably engages. A spring 33 constantly urges the valve member 26 to a normally closed position. An intake hose or flexible duct 34 is connected with the connector 29 and is of substantial length so that the opposite end of the hose or duct 34 may be positioned adjacent the head of a patient from which the moisture is being withdrawn.

The head 23 is formed with an outlet or exhaust opening 35 having a valve seat 36 on which an exhaust valve 37 normally engages. An upstanding cylindrical housing 38 is fixed to the upper side of the head 23 and extends upwardly from the exhaust port 35. A valve stem guide member 39 is disposed interiorly of the housing 38 and the stem 40 of the valve 37 slidably engages through the guide 39. A spring 41 constantly urges the valve member 37 to a normally closed position. The housing 38 has a cap 42 detachably mounted on the upper end thereof and the housing 38 is also formed with a laterally extending exhaust nipple 43. A moisture collector or receiver 44 is disposed on one side of the cylinder 18 and includes a threaded cap 45 mounted on the upper end of the receptacle 46. The receptacle 46 may be made of transparent material and the cap 45 made of metal or other suitable material.

The collector 44 is held in outstanding relation with respect to the cylinder 18 by means of a receptacle supporting ring 47 which is fixed to the cap 45. The ring 47 includes a pair of inwardly extending arms 48 having an eye 49 engageable beneath the head of a fastening member 24. In order to provide a means whereby the transparent receptacle 46 may be held against breakage by contact with the metal forming the suction member 14, a rubber ring 50 is mounted on the receptacle member 46 to a point adjacent the lower end thereof and the rubber or resilient member 50 is adapted to engage the upper portion of the base 15. The cap 45 is provided with

an upwardly extending intake nipple 51 about which a flexible hose 52 is adapted to engage. The opposite end of the hose 52 is adapted to telescope the nipple 43 so that the water and air discharged through the nipple 43 will be discharged into the collector 44. The cap 45 is also provided with a second upstanding nipple 53 disposed in spaced relation to the nipple 51 with which one end of an outlet hose 54 is adapted to engage.

A combined suction and exhaust hood and hair heating member generally designated as 55 is adapted to be connected to the opposite ends of the hose 34 and the hose 54. The hood structure 55 includes an outer shell or housing 56 which is outwardly flared and is substantially oval in transverse section. The outer shell or housing 56 is formed with a rear wall 57 at the reduced end thereof and a nipple 58 constituting the suction portion of the hood, is fixed to the wall 57. The hose 34 is adapted to telescope over the nipple 58. The large end of the outer shell 56 is formed with a marginal flange 59 about which a rubber casing 60 is adapted to engage. An inner hood 61 is mounted within the outer shell or casing 56 and is substantially smaller in size than the outer shell 56 so as to thereby form an air space 62 therebetween. The inner hood 61 is formed with a rear wall 63 at the small end thereof and the nipple 58 is also fixed to the end wall 63 so that the moisture will be withdrawn through the inner hood 61.

The inner hood 61 has secured to the large end thereof a screen or pervious wall 64 so that hair or the like will not be drawn into the interior of the hood 61. The outer shell 56 has fixed thereto an intake nipple 65 constituting the exhaust portion of the hood, with which the opposite end of the hose 54 is adapted to engage. The heated air which is discharged from the combined suction and pressure member 14 is adapted to be discharged in the chamber or air space 62 and about the outer surface of the inner hood 61. Preferably, the outer end of the inner hood 61 is disposed inwardly from the rubber covering 60 so that the air discharged against the hair from the chamber 62 will pass beneath the perforate front wall 64 in order to more quickly dry the hair which is disposed in confronting position to the drying hood 55.

The crank shaft 21 has secured to one end thereof a grooved pulley 66 and an endless belt 67 is trained about the pulley 66. An electric motor 68 is disposed in laterally spaced relation with respect to the combined suction and pressure member 14 and is mounted on an adjustable platform 69 by fastening devices 70. The platform 69 is formed at the opposite edges thereof with depending flanges 71 which engage on opposite sides of the flanges 23 of the base 10.

The platform 69 is rockably supported from the base 10 by means of pivot members 72 which engage through the flanges 71 and the flanges 13 adjacent the forward end portions of the flanges 71. An upwardly extending threaded bolt 73 is fixed as at 74 to the base plate 11 and extends upwardly through an opening 75 which is formed in the platform 69. A nut 76 is threaded under the bolt 73 so as to provide for tightening of the belt 67. The motor 68 has a grooved pulley 77 mounted on the armature shaft 78 thereof and the belt 78 is also trained about the pulley 77.

A handle generally designated as 79 is secured to the combined suction and exhaust member 14 and includes a shank 80 provided with a

boss 81 at the lower end thereof which is secured by a fastening device 82 to the upper end portion of the base member 15. A laterally extending handle member 83 is formed integral with the upper end of the shank 80 and extends laterally or rearwardly from the cylinder 18. The shank 80 also has formed integral therewith a forwardly extending lug 84 which is adapted to engage between a pair of the heat dissipating vanes 19 so that tightening of the single bolt 82 will firmly hold the handle structure 70 onto the combined suction and exhaust member 14.

In the use and operation of this device, the motor 68 is adapted to be connected to a suitable source of electric current supply so as to operate the combined suction and exhaust member 14. The hair drying and dehydrating hood 55 is held in one hand of the operator and moved over the hair of the person. The moisture will be drawn into the inner hood member 61 on the suction or downward stroke of the piston 20 and on the upward stroke of the piston 20 which is the compression stroke, the valve member 26 will be disposed in a closed position, whereas the valve member 37 will be open and the hair and moisture compressed in the cylinder 18 will be forced through the valve housing 38 into the collector 44.

The free moisture will be collected within the collector 44, whereas the air which is heated by the friction of the piston 20 in the cylinder 18 will be forced out of the collector 44 through the outlet nipple 53. The heated air passing from the collector 44 will be forced through the hose 54 into the air chamber 62 and about the inner shell 61 so as to thereby heat the hair which is disposed within the area of the open or large end of the hood structure 55.

With a device of this kind, the hair may be dried more quickly than is now the practice wherein a heated hood is disposed in encompassing position with respect to the head of a person, and the person is subjected to a considerable amount of heat until the hair becomes dry. Also with a device of this kind the hair may be dried more quickly without discomfort of the heated hood.

In order to provide a means whereby the air in the exhaust hose 54 may be positively heated, an electrical heating element 85 is interposed in the hose 54 and connected to a source of current supply. In this manner the air passing through the hose 54 may be heated to the desired degree independent of the heat generated by the compressor 14.

What I claim is:

1. In a hair drier and dehydrator, a pump comprising a cylinder, annular spaced apart heat dissipating vanes carried by said cylinder, a crank case below said cylinder, a handle, means securing one end of said handle to said crank case, an arcuate member engaging between a pair of said vanes, and means connecting said arcuate member to said handle, said arcuate member correlated with the handle securing means to hold the handle against turning.

2. In a hair drier and dehydrator, a pump comprising a cylinder, annular spaced apart heat dissipating vanes carried by said cylinder, a crank case below said cylinder, an L-shaped handle having one side parallel with said cylinder and the other side extending at right angles from said cylinder, means securing said one side of said handle to said crank case, an arcuate member en-

gaging between a pair of said vanes, and means connecting said arcuate member to said handle, said arcuate member correlated with the handle securing means to hold the handle against turning.

3. A hair drier comprising a combined air suction and exhaust pump, a hood provided with air supply and exhaust ports and comprising spaced inner and outer shells open at one end for the passage of air, means connecting the suction side of said pump to the suction portion of said hood, means connecting the exhaust side of said pump to the exhaust portion of said hood, means for heating the air, a moisture collector interposed in said second connecting means, and means supporting said collector from said pump, said supporting means including a threaded cap, a pair of arms fixed to said cap, and means securing said arms to said pump.

4. A hair drier comprising a reciprocable suction and exhaust pump, valved intake and exhaust housings carried by said pump, a hood provided with air supply and exhaust ports and comprising spaced inner and outer shells open at one end for the passage of air, means connecting the suction portion of said hood to said intake housing, means connecting the exhaust portion of said hood to said exhaust housing, means for heating the air, a moisture collector interposed in said

second connecting means, means supporting said collector from said pump, said supporting means including a threaded cap, a pair of arms fixed to said cap, means securing said arms to said pump, and operating means for said pump.

5. A hair drier comprising a reciprocable suction and exhaust pump, valved intake and exhaust housings carried by said pump, a hood provided with air supply and exhaust ports and comprising spaced inner and outer shells open at one end for the passage of air, means connecting the suction portion of said hood to said intake housing, means connecting the exhaust portion of said hood to said exhaust housing, means for heating the air, a moisture collector interposed in said second connecting means, means supporting said collector from said pump, said supporting means including a threaded cap, a pair of arms fixed to said cap, means securing said arms to said pump, operating means for said pump, a base, means mounting said pump on said base, a rockable platform carried by said base, means securing said operating means on said platform, a flexible drive element between said operating means and said pump, and means for adjusting said platform relative to said base to maintain said drive element taut.

WALTER D. NICOL.
